(57) **CLAIM**

I claim the ornamental design for a cat toy, as shown.

DESCRIPTION

FIG. 1 is a perspective view showing the front, top, and left side of a cat toy embodying the design of my invention;

FIG. 2 is an elevation view of the right side;

FIG. 3 is an elevation view of the back;

FIG. 4 is a plan view of the bottom; and,

FIG. 5 is a perspective view of a second embodiment of FIG. 1 that includes eye-simulating graphics, ear-simulating graphics, and whiskers-simulating graphics.
